Dec. 1481

Elemir J. Key, of Lowell, Mass.
Assignor to
Lowell Manufacturing Co. of same place.
Letters Patent No 116, dated Oct. 22, 1861.
Whole No. 1481.

The schedule referred to in these Letters Patent and making part of the same.

To all whom it may concern:

See it known that I, Elemir J. Key, of Lowell, in the
County of Middlesex, and State of Massachusetts, have originated and designed
a new Pattern for Carpets, or other fabrics, of which the following is a full, clear
and exact description, reference being had to the accompanying drawings,
making part of this specification.

A.A.A. are octagonal figures the interiors of which are
occupied by small blocks, diamonds and key work. Lying between these octagons are
the cross shaped figures B.B. each supporting a small block 1. When the design is match-
ed, other figures, similar to the octagons A.A.A. and crosses B.B. are formed, which
alternate each other throughout the design.

The colors employed for the different portions of the design, may
may be varied to suit the taste and wants of the manufacturer.

Claim.

What I claim as my invention, and desire to secure by
Letters Patent, is the design or pattern, for carpets or other fabrics, herein set forth.

Witnesses,

Andrew C. Swafford.
Chas. H. Galman.
